UNITED STATES PATENT OFFICE

144,807

DESIGN FOR A PENDANT

Carl Schraysshuen, Providence, R. I.

Application November 8, 1945, Serial No. 123,586

Term of patent 7 years

(Cl. D45—15)

To all whom it may concern:

Be it known that I, Carl Schraysshuen, a citizen of the United States, residing at Providence, in the county of Providence and State of Rhode Island, have invented a new, original, and ornamental Design for a Pendant, of which the following is a specification, reference being had to the accompanying drawing constituting a part thereof:

Fig. 1 is a front elevational view of a pendant showing my new design; and
Fig. 2 is a side view thereof.

I claim:

The ornamental design for a pendant, substantially as shown.

CARL SCHRAYSSHUEN.
